(57) **CLAIM**

The ornamental design for a post-surgical dressing, as shown and described.

DESCRIPTION

FIG. 1 is a front left perspective view of the design for a post-surgical dressing;

FIG. 2 is a front elevational view of the design as seen in FIG. 1;

FIG. 3 is a rear elevational view of the design as seen in FIG. 1;

FIG. 4 is a left side elevational view of the design as seen in FIG. 1;

FIG. 5 is a right side elevational view of the design as seen in FIG. 1;

FIG. 6 is a top plan view of the design as seen in FIG. 1;

FIG. 7 is a bottom plan view of the design as seen in FIG. 1;

FIG. 8 is a front elevational view of the design as seen in FIG. 1, at a fully folded position;

FIG. 9 is a front elevational view of the design as seen in FIG. 1, at a partially folded position; and,

FIG. 10 is a front elevational view of the design as seen in FIG. 1, at a spread out position.

The broken lines shown in FIGS. 1-10 depict stitching seams on the post-surgical dressing that form no part of the claimed design.

1 Claim, 9 Drawing Sheets
